(57) **CLAIM**

The ornamental design for an ultrasound therapeutic treatment transducer, as shown and described.

DESCRIPTION

FIG. 1 is a top left rear perspective view of a first embodiment of an ultrasound therapeutic treatment transducer embodying the new design.

FIG. 2 is a bottom right front perspective view thereof.

FIG. 3 is a top view thereof.

FIG. 4 is a bottom view.

FIG. 5 is a rear view.

FIG. 6 is a front view.

FIG. 7 is a left view.

FIG. 8 is a right view.

FIG. 9 is a top left rear perspective view of a second embodiment of an ultrasound therapeutic treatment transducer embodying the new design.

FIG. 10 is a bottom right front perspective view thereof.

FIG. 11 is a top view thereof.

FIG. 12 is a bottom view.

FIG. 13 is a rear view.

FIG. 14 is a front view.

FIG. 15 is a left view.

FIG. 16 is a right view.

FIG. 17 is a top left rear perspective view of a third embodiment of an ultrasound therapeutic treatment transducer embodying the new design.

FIG. 18 is a bottom right front perspective view thereof.

FIG. 19 is a top view thereof.

FIG. 20 is a bottom view.

FIG. 21 is a rear view.

FIG. 22 is a front view.

FIG. 23 is a left view.

FIG. 24 is a right view.

FIG. 25 is a top left rear perspective view of a fourth embodiment of an ultrasound therapeutic treatment transducer embodying the new design.

FIG. 26 is a bottom right front perspective view thereof.

FIG. 27 is a top view thereof.

(Continued)

FIG. 28 is a bottom view.

FIG. 29 is a rear view.

FIG. 30 is a front view.

FIG. 31 is a left view; and,

FIG. 32 is a right view.

Broken lines are used to illustrate features of the ultrasound therapeutic treatment transducer which form no part of the claimed design.
